IRONING TABLE

Bert Bryan, La Fayette, Ind.

Application June 15, 1937, Serial No. 148,368

2 Claims. (Cl. 38—127)

The invention relates to an ironing board and more especially to a foldable or collapsible ironing table.

The primary object of the invention is the provision of a table of this character, wherein the ironing board proper can be set up for use and when set up the board will be held rigid and is a proper height for convenience in the ironing of clothes or the like, the ironing board proper being adjustable to any desirable height to suit the convenience of a user of the same.

Another object of the invention is the provision of a table of this character, wherein on the collapsing or folding thereof it will be compact and can be readily stored within the least possible space as well as being latched in its folded or collapsed condition, the table being readily portable for convenience in the placing of the same for use.

A further object of the invention is the provision of a table of this character, which is simple in its construction, thoroughly reliable and effective in operation, strong, durable, readily and easily folded or set up for use and inexpensive to manufacture.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is a perspective view of the ironing table constructed in accordance with the invention set up for use.

Figure 2 is a fragmentary vertical longitudinal sectional view through the same taken on the line 2—2 of Figure 1.

Figure 3 is a sectional view on the line 3—3 of Figure 1.

Figure 4 is an elevation of the table folded or collapsed and looking toward the rear thereof.

Figure 5 is a view similar to Figure 4 looking toward the opposite side of the table.

Figure 6 is a top plan view with the table folded.

Figure 7 is a fragmentary sectional view on the line 7—7 of Figure 1.

Figure 8 is a sectional view on the line 8—8 of Figure 7.

Figure 9 is a sectional view on the line 9—9 of Figure 7.

Figure 10 is a fragmentary vertical sectional view showing in detail one of the strap-like hangers employed with the table.

Figure 11 is a fragmentary side elevation thereof.

Similar reference characters indicate corresponding parts throughout the several views in the drawings.

Referring to the drawings in detail, the ironing table A is of the collapsible or foldable type and comprises a substantially rectangular shaped main frame 10 adapted for positioning vertically and to rest upon a foundation or support while centrally of this frame are longitudinally disposed spaced parallel rack bars 11, these being made secure to opposite ends of the said frame. In the inner faces of the side rails of the frame 10 are longitudinally extended channels or grooves forming guideways 12 for a turning or pivot arbor 13 carrying an ironing board 14, the arbor being made fast thereto at its inner end in any suitable manner. This board 14 is susceptible of vertical swinging movement and has fixed to its under side intermediate of its ends a pair of spaced pivot bearings 15 for pivots 16 swingingly connecting thereto the spaced arms 17 of a prop including a cross arbor 18 which slidably fits the channels or grooves 12 in the side rails of the frame 10, the arbor 13 being also slidably engaged in the channels or grooves 12 of said frame for adjustment of the board 14.

Engaged with the arbor 18 of the prop including the arms 17 is a pair of loop-like hanger straps 19, these being engaged with the arbor 13 of the board 14 and limit the displacement of the said board and prop with respect to each other so that when the board 14 is swung to a horizontal plane the prop including the arm 17 and arbor 18 will be held at an angle to said board and in propping position.

The frame 10 intermediate thereof has swingingly connected thereto a prop including the forwardly convergent arms 20, these being detachably pivoted at 21 to the side rails of the said frame 10 and also has pivoted between the same at 22 a latching bar 23, the pivotal connection 22 between the latter and the said arms 20 being at the outer ends of these arms. This latching bar 23 is provided with a notch 24 for engaging the end cross rail 25 of the frame 10 which is at the bottom end of the said frame and in this manner the latter will be held in upright supported position as the prop including the rails 20 will function as a supporting leg for the frame.

The loop-like hanger straps 19 are confined within the grooves or channels 12 in the side rails of the frame 10.

Secured to the board 14 at the end having the

arbor 13 are brackets 26 which are outside of the rack bars 11 and pivotally support a swinging keeper bail 27 adapted for selective engagement in notches 28 in the rack bars 11 to hold 5 the board 14 in adjusted position within the frame 10 and at different elevated horizontal planes. Thus it can be seen from Figures 1 and 10 of the drawings that the board 14 can be raised and lowered relative to the frame 10 for placing 10 the said board at any desired horizontal plane convenient to the user thereof.

On disengaging the bail 27 from the rack bars 11, the board 14 can be folded against the frame 10 and in this position can be latched by a latching hook 29 swingingly connected at 30 to the frame at one side thereof and coacting with a keeper eye 31 on said frame at the other side thereof.

The prop including the arms 20 and the latching bar 23 can be readily folded with relation to the frame 10 on unlatching the bar 23 from the end rail 25 of said frame. The latching hook 29 overlies the prop including the arms 17 for the board 14 as well as the latter when the said hook is engaged with the keeper eye 31 and in this manner the board 14 is sustained in folded position.

The table A can be readily set up with dispatch for use and also conveniently collapsed or folded 30 when not in use, being compact and occupying the least possible space when in folded or collapsed condition.

What is claimed is:

1. An ironing table comprising a vertically disposed frame having side channels, an ironing board having a foldable prop, arbors for the board and prop slidably fitting in the said channels in said frame, a prop for said frame and foldable relative thereto, vertically disposed rack bars fitted in the frame and having notches, a bail carried by the board and vertically movable for engaging the notches in the rack bar, and loop-like straps engaged with the board and the prop therefor and slidably confined within the channels for effecting a movable engagement between the respective arbors of the board and the prop. 10

2. An ironing table comprising a vertically disposed frame having side channels, an ironing board having a foldable prop, arbors for the board and prop slidably fitting in the said channels in said frame, a prop for said frame and foldable relative thereto, vertically disposed rack bars fitted in the frame and having notches, a bail carried by the board and vertically movable for engaging the notches in the rack bar, loop-like straps engaged with the board and the prop 20 therefor and slidably confined within the channels for effecting a movable engagement between the respective arbors of the board and the prop, and means on the frame for latching the board and prop in folded relation thereto. 25

BERT BRYAN.
